Patented Dec. 17, 1918.

Fig. 1

UNITED STATES PATENT OFFICE.

ROBERT GEORGE REA, OF WINNIPEG, MANITOBA, CANADA.

CAR-REPLACER.

1,287,747.

Specification of Letters Patent. Patented Dec. 17, 1918.

Application filed April 11, 1917. Serial No. 161,204.

To all whom it may concern:

Be it known that I, ROBERT GEORGE REA, a citizen of the Dominion of Canada, residing at the city of Winnipeg, in the Province of 5 Manitoba and the Dominion of Canada, have invented certain new and useful Improvements in Car-Replacers, of which the following is a specification.

My invention relates to devices which are 10 used in case of the derailment of a railway car, to replace the car upon the tracks, and the object of the invention is to provide a device of this character which may be carried as a part of the regular equipment of 15 railway trains and which may be readily positioned for use in case of accident and without the necessity of either cutting the rails or spiking the device to the sleepers. With this and certain other objects in view which 20 will appear as the description proceeds, the invention consists in the novel construction and combination of parts first described in the following specification and then more particularly pointed out in the appended 25 claims, reference also being had to the drawings forming part hereof, in which similar characters of reference indicate similar parts throughout the different views, and in which—

30 Figure 1 is a plan view of the device as it would appear when positioned for use in connection with a railway track.

Fig. 2 is an elevation from the inside, of 35 that portion of the mechanism which is hooked upon the rail upon the right hand side of the track, the view being in the direction indicated by the arrow.

Fig. 3 is an elevation of the corresponding 40 side of that member which is hooked upon the opposite or left hand rail.

Fig. 4 is a sectional end view of the member shown in Fig. 2 and on the line 4 therein.

Fig. 5 is a similar view taken on the line 5 in Fig. 3.

45 Fig. 6 is a bottom plan view of the member shown in Fig. 3.

Fig. 7 is a view in perspective of the switch member pertaining to the member shown in Fig. 2, when the arrangement of 50 parts is such as shown in Fig. 1.

Fig. 8 is the switch member pertaining to that member shown in Fig. 3, under a similar arrangement of parts.

55 Fig. 9 is a view similar to that shown in Fig. 7 but with the switch member added to show the connection from the under side.

In Fig. 1 the device is shown in connection with a track having the usual rails A and B, supported on sleepers C, the arrangement shown contemplating the replacing of a derailed car having its off wheels straddling the rail B at the left hand side of the figure, and the parts of the device will be first described in their relation to the arrangement shown. In this the replacer comprises a 65 pair of body members indicated as D and E, having longitudinal channels 4 and 5 respectively, on their under sides, to receive the heads of the rails and offset recesses 6 to receive the base flanges thereof. The member D in the present arrangement pertains to the rail A and that E to the rail B, these positions being however, interchangeable under the circumstances hereinafter touched upon, and the members are merely hooked upon 70 the rails by their channels, the members each being provided with a base plate 7 extending lengthwise of the same and adapted to rest upon the sleepers at the side of the rail. 75

The upper surfaces of the members D and 80 E are preferably made to crown on a true curve from end to end as shown at 8 in Fig. 3, with the highest point at the center, and the plane of the surface in the case of the member D is cut by the grooves 9 and 10, 85 which, starting at the extremities of the member in line with the inner side of the head of the rail A, run diagonally inward to meet and run out at the point 11, the member being here cut down to the bed plate 7 in 90 line with the grooves, the faces 12 and 13 thus produced on the member forming continuations of the respective grooves 9 and 10.

The grooves 9 and 10 are provided to receive the flange of a car wheel and the rail portions 14 and 15 of the device are defined by the V-shaped portion 16 which is produced on the member by lowering the surface thereof slightly at rail width distance 100 from the grooves 9 and 10.

The removal of the V-shaped portion 16 of the member operates to reduce weight but has no effect whatever on the function of the device. 105

The cutting of the surface of the member D by the grooves 9 and 10 isolates the triangular rail portions 14^a and 15^a from the remainders 14 and 15 thereof but does not impair their relationship. The parts 14^a 110 and 15^a, it will be noted, are entirely outside of the line of the rail A and the ends

of the said parts are reduced in thickness from the top down approximately half the depth of the member to provide a semi-circular socket 17 at each end, the unreduced portions 18 being rounded on the outside and pierced through vertically to form the slots 19 lying in the longitudinal direction of the member and opening into the circular depressions 20 formed in the under sides of 10 the portions 18.

The member E as previously stated is connected with the rail B by hooking it there-over and the plane of its surface is cut diagonally by the grooves 21 and 22, these 15 however, unlike those in the case of the member D, starting at the outer edge of the rail B and running inwardly to meet and run out at the point 23. The triangular rail portions 24^a and 25^a are on the inside 20 and the main rail portions 24 and 25 are on the outside. The vertical faces 26 and 27 of the member in this case define the outer edges of the rail portions 24 and 25 and the extremities of these are reduced to form 25 the sockets 28, leaving the rounded portions 29 at each end having the slots 19 therethrough and the circular recesses 20 therebelow.

A tapered switch member F has a rounded 30 projection 30 at its thicker end and a socket 31 therebelow, to loosely fit the respective socket 17 and projection 18 on the end of the member D, the projection 30 on the switch having a depending stud 32 provided with a cross head 33 adapted to pass 35 through the slot 19 into the recess 20 when the switch and member are approximately at right angles to each other, the ends of the switch and member being shaped to permit of this positioning as is clearly shown 40 in the drawings, the switch being thus detachably and pivotally connected with the member.

The switch member has a longitudinal 45 groove 34 at its inner side to register with the groove 10 in the member, the remainder of the surface forming a rail portion to coöperate with those 15^a and 15 on the member D.

50 Similarly, a switch member G has a projection 35 and a recess or socket 36 to interconnect with those 28 and 29 on the member E in the manner of a hinge, and a stud 37 with a cross head 38 to pass through the 55 slot 19 in the projection 29 on the member to complete the hinge or pivotal connection.

It will be noted that as the studs on the switch members are positioned in slots rather than circular openings there is a considerable 60 latitude possible in the relative positions of the switches to the hooked members for a reason which will be clearly apparent to persons familiar with the art.

The switch G is also provided with a 65 longitudinal groove, 39, to register with the

groove 21 in the member E, and the rail portion 40 to register with the rail portion 24 on the member.

The rail portions on both switches are beveled back as at 41 to facilitate entry of 70 the car wheel flanges into the grooves.

The under sides of the points of the switches are provided with sharp points 42 which penetrate the faces of the sleepers upon which they rest and prevent slipping. 75

In operation, should a car be derailed in the position previously mentioned, that is to say, with its wheels off on the left and straddling the rail B, the members D and E would be positioned as shown in Fig. 1 80 and the switches F and G moved pivotally till they faced the rims of the wheels. Power would then be applied to pull the car to the right when the derailed wheels would pass up the switch members with their 85 flanges in the grooves in the switches, thence on over the members D and E till they passed off the opposite sides thereof onto the rails A and B.

Had the car been derailed to the right and 90 with its wheels straddling the rail B the switch members would have been changed across and that F would have been connected with the opposite end of the member E while that G would have been connected with the 95 opposite end of the member D, the changing across being necessary to bring the grooves in the switches and members into register.

On the other hand, if the car had been derailed with its wheels straddling the rail A, 100 the members D and E would have been turned around and that D hooked on the rail B while that E was placed on the rail A. The switches would also be changed around in accordance with the direction in 105 which it appeared desirable to replace the car.

Thus the members are interchangeable and their switches directable to suit almost any case of derailment, while the surfaces 110 of both provide the necessary rail and groove means to direct the car wheels in either direction back to their proper place on the rails and the tapered shape of the switches provides the necessary easy grade. 115

The members may of course be hollowed at certain points to reduce weight and the details of construction varied in many ways without however departing from the spirit of the invention or the scope of the appended claims. 120

From the foregoing it will further be clearly apparent to any one skilled in the art, that if the members D and E are effective to direct the car wheels across the rails 125 in a replacement they may be made equally useful to derail a car, and that if the ends of a pair of switch rails be properly positioned and spiked to the ties, and the said members positioned on the regular rails to 130

direct the car wheels toward the said switch rails, they will form a switch and so avoid cutting of the regular rails when a temporary switch line becomes desirable.

5 What I claim is,—

1. A car replacer having a body, means to hook the body on a rail, a tie abutting flange, a diagonally directed tread surface and a groove into which the edge of the 10 tread surface merges, a switch member pivotally end connected to the body medially of the end of the tread surface thereon for partial rotation around the body and having an inclined tread surface and a groove 15 leading to the similar parts of the body.

2. A car replacer comprising a pair of body members, one adapted for the outer and the other for the inner side of rails, diagonally directed tread surfaces on the 20 body members, grooves into which the edges of the tread surfaces merge, a pair of inclined switch members, tread surfaces on the switch members, grooves at the sides of the tread surfaces, and releasable pivotal connecting means on the switch and body members in line with the tread surfaces on each. 25

3. A device of the kind described comprising body members adapted to be hooked over rails, diagonally directed tread surfaces on the body members extending beyond the 30 line of the said rails a distance greater than the width of the said rails, whereby the ends of switch rails may be made to register with the ends of the said tread surfaces, and grooves at the sides of the tread surfaces on 35 the body members adapted to coincide with the sides of the said switch rails.

4. A derailing device comprising a pair of body members shaped to removably hook over railway rails and to abut upon the 40 sleepers supporting the same, tread surfaces on the body members adapted to support a car wheel out of contact with the said railway rails, and grooves on the body members adapted, that on the one member to receive 45 the flange of and guide the car wheel on one side clear across a rail and the groove on the other member to similarly receive and guide the opposite wheel to a switch rail.

In testimony whereof, I affix my signature. 50

ROBERT GEORGE REA.
